PHONOGRAPH CABINET

John W. Mason, Glenview, Ill., assignor to Admiral Corporation, Chicago, Ill., a corporation of Delaware

Application August 18, 1958, Serial No. 52,257

Term of patent 3½ years

(Cl. D56—4)

Fig. 1.

Fig. 2.

Fig. 1 is a front perspective view of a phonograph cabinet, showing my new design; and

Fig. 2 is a side elevational view thereof.

The left side of the cabinet is similar to the right side and the back and bottom are plain.

The dominant features of my design reside in the portions shown by full lines.

I claim:

The ornamental design for a phonograph cabinet, as shown and described.
